(57) **CLAIM**

The ornamental design for an apparatus support device holder, as shown and described.

DESCRIPTION

FIG. 1 is a front view of an apparatus support device holder, FIG. 2 is a right side view of the apparatus support device holder shown in FIG. 1,

FIG. 3 is a left side view of the apparatus support device holder shown in FIG. 1,

FIG. 4 is a right side perspective view of the apparatus support device holder shown in FIG. 1 showing also part of the rear side, and

FIG. 5 is a left side perspective view of the apparatus support device holder shown in FIG. 1, showing also the part of rear side of the apparatus not shown in FIG. 4; and,

FIG. 6 is a bottom view of the apparatus support device holder shown in FIG. 1.

The apparatus support device holder is used for supporting an apparatus support device specifically adapted to cradling a particular apparatus such as a wireless phone, GPS, a PDA device, a telephone or other equipment in a convenient position on a smooth surface such as a windshield of a motor vehicle.

The three small protrusions shown on the surface of the locking mechanism in FIGS. 2 and 3 should be shown in broken lines as they form no part of the claimed design. But, because of their small size, the broken lines cannot be clearly shown and are additionally described in this statement for clarity.

The portions of the apparatus support device holder shown in broken line form no part of the claimed design.
